INVENTOR.

UNITED STATES PATENT OFFICE.

JAMES RYAN, OF BROOKLYN, E. D., NEW YORK.

IMPROVEMENT IN FLESH AND BATH BRUSHES.

Specification forming part of Letters Patent No. 146,713, dated January 20, 1874; application filed September 27, 1873.

To all whom it may concern:

Be it known that I, JAMES RYAN, of Brooklyn, E. D., in the county of Kings and State of New York, have invented certain Improvements in Flesh and Bath Brushes, of which the following is a specification:

This invention pertains to that class of devices used for chafing the surface of the body during or after a bath, as may be desired; and the invention consists in providing the ordinary or well-known brush with adjustable handles, by which the brush may be readily adapted to be used directly in the hand, or be provided with a long handle for use over the back or parts not otherwise conveniently reached, as will be hereafter explained.

Figure 1 is a perspective view of the brush complete, showing both handles attached, or, more properly, the long handle and the adjustable band or strap for binding the brush to the hand when desired. Fig. 2 is a transverse section through the middle of the brush and hand-strap over the back. Fig. 3 is a longitudinal section through the center of Fig. 1. Fig. 4 is a modification, showing another method of fastening the long handle in the brush-head.

At A is represented an ordinary brush for use as a flesh or bath brush; but to make it adaptable to various sizes of hands, the strap at B, that is made to surround the back of the hand in grasping the brush, is provided with adjustable slides or attachments, similar to such as are used in suspenders, so that the hand-strap may be shortened or lengthened, as desired.

A buckle of the ordinary construction may

be used, but it is not so convenient nor so desirable.

Again, to adapt the brush for being used on the back and shoulders, a long handle, as at C, is provided, and fitted in any suitable manner to connect with the brush, one plan of said attachment being shown at Fig. 1, where the handle is fitted into a dovetail slot in the back of the brush, a cross-section of which is shown at D, Fig. 2, and it may be held in position by a button on the end of the handle, as shown at E, Figs. 1 and 3; or a more durable method would be by a spring-catch, as shown at F, Fig. 4, where the longitudinal strength of the spring is utilized, and if placed underneath, the handle may be concealed, except the knob on the end, as shown at G. A similar spring may also be applied on the top of the handle, and have its projecting end bent down to catch upon the end of the brush-head itself.

It is evident, also, that the handle may be attached to the brush in other ways besides the dovetail slot, as a T-slot would answer the same purpose, and the counterparts may also be made of metal and attached to the back of the brush-head in any suitable manner.

I therefore claim—

As a new article of manufacture, a flesh-brush possessing an adjustable band, B, and a detachable handle or arm, C, all constructed and arranged substantially as shown and described, for the purposes herein set forth.

JAMES RYAN.
